Inventor,

Carl M. Hanna

UNITED STATES PATENT OFFICE.

CARL M. HANNA, OF DEL NORTE, COLORADO.

SORTING MACHINE.

Application filed June 2, 1921. Serial No. 474,353.

To all whom it may concern:

Be it known that I, CARL M. HANNA, a citizen of the United States, residing at Del Norte, in the county of Rio Grande and State of Colorado, have invented certain new and useful Improvements in Sorting Machines, of which the following is a specification.

This invention relates to an improvement 10 in sorting machines and it has for its object to provide a simple, efficient and rapid working device adapted to sort large and small vegetables (or fruits) from one another, and convey the sorts to different receptacles therefor.

Another object of the invention is to provide the combination of a rotary screen and conveyor, whereby the screen may sort out large from small vegetables, such as potatoes, etc., and deliver them to the conveyor from which they are deposited into different receptacles.

A still further object of the invention is to provide in combination with a sorting 25 machine a sack-holding device whereby sacks may be held open to receive sorts from a conveyor.

A still further object of the invention is to provide a sorting screen in combination 30 with runners upon which the machine is mounted whereby said machine may be readily moved from one place to another.

With the above and other objects in view, I have invented the device illustrated in the 35 accompanying drawings, in which:

Figure 1 is a side elevational view of my improved sorting machine,

Figure 2 is a top plan view thereof,

Like reference characters indicate like 40 parts throughout the following specification and in the several views in the drawings, in which 1 indicates a sorting machine consisting of a frame work 2 mounted upon runners 3 and 4. The forward end of said

45 machine is provided with a hopper 5 for receiving vegetables, such as potatoes, or fruits, such as apples, peaches, etc. Mounted in one side 6 of said hopper is the end 7 of a shaft 8, the other end of which 50 has a bearing in a bearing member 9 mounted on the wall 10. On the end 11 of the shaft 8 is a bevel gear 12 in mesh with a bevel gear 13 on a shaft 14 supported by the bearing 15 at one end and in the side wall 55 16 of the frame 2 at its other end. This shaft is rotated by means of a sprocket

wheel 17 driven by the sprocket chain 18 which in turn is driven by a sprocket wheel 19 operated by a hand crank 20. Fixed to rotate upon the shaft 8 is a cylindrical 60 screen 21, the mesh of which may be of any desired size in order to permit culls or small vegetables or fruits to fall there-through on to the endless conveyor 22. This conveyor carries the culls to the end 65 23 of the machine. They are guided however by means of the inclined guide board 24 to the passage way 25 between the side wall 26 of the machine and the division wall 10 thereof, from whence they are deposited by said conveyor in a sack 27 mounted upon the sack holder 28. The product being separated which will not pass through the mesh of the screen 21 will fall through the opening 29 of the screen into the passageway 30 and onto the conveyor which will carry the same to the sack 31. Pivotally connected to the gear 32 operated by the combined gear and sprocket wheel 19 is an agitator rod 33, the other end of which 70 is pivotally mounted upon the crank 34, one end of which projects into the hopper 5 and operates the kicker 36 whereby the contents of the hopper is caused to continually gravitate to and from the spout 75 37 into the end 35 of the screen 21.

From the above description, it will readily be seen that I have provided a simple and very efficient fruit and vegetable separator that may be operated rapidly and with comparatively little exertion. The gear wheel 80 32 is fixedly mounted upon and operates a shaft 38 over which the conveyor 22 passes and by means of which it is operated, the other end of said conveyor operating over 85 an idler shaft 39.

Having described my invention, that which I claim to be new is:

1. A device of the character described 100 consisting of a trough having an endless conveyor bottom throughout its length, a division wall, a hopper, a shaft parallel with said conveyor supported by said hopper and division wall forming two passages, a cylindrical screen fixedly mounted upon said shaft to rotate therewith said screen having open ends one of which aligns with said hopper and the other of which aligns with one of said passages.

2. A device of the character described 110 consisting of a trough having an endless conveyor bottom throughout its length, a

- division wall, a hopper, a shaft parallel with said conveyor supported by said hopper and division wall forming two passages, a cylindrical screen fixedly mounted upon said shaft to rotate therewith said screen having open ends one of which aligns with said hopper and the other of which aligns with one of said passages, one end of said shaft extending over said division wall, a gear on said end and means for operating said gear.
3. A device of the character described consisting of a trough having an endless conveyor bottom throughout its length, a division wall, a hopper, a shaft parallel with said conveyor supported by said hopper and division wall forming two passages, a cylindrical screen fixedly mounted upon said shaft to rotate therewith said screen having open ends one of which aligns with said hopper and the other of which aligns with one of said passages, one end of said shaft extending over said division wall, a gear on said end and means for operating said gear, said means being at the end of said trough opposing said hopper.
4. A device of the character described consisting of a trough having an endless conveyor bottom throughout its length, a division wall, a hopper, a shaft parallel with said conveyor supported by said hopper and division wall forming two passages, a screen fixedly mounted upon said shaft to rotate therewith said screen having open ends one of which aligns with said hopper and the other of which aligns with one of said passages, one end of said shaft extending over said division wall, a gear on said end and means for operating said gear, said means being at the end of said trough opposing said hopper, said means being adapted to actuate said conveyor.
5. A device of the character described, including a trough, a hopper at one end of said trough, a shaft mounted parallel and substantially centrally of said trough and a rotatable screen mounted upon said shaft, an endless conveyor forming the bottom of said trough and operating parallel with said screen throughout its length, a division wall mounted in proximity to the medial line of said trough, and forming a support for one end of said shaft, said hopper forming a bearing support for the other end of said shaft, said screen being cylindrical and having its ends open, said hopper having an outlet into one of said open ends, a shaft mounted transversely of said trough and gears connecting said shafts.
6. A device of the character described, including a trough, a hopper at one end of said trough, a shaft mounted parallel and substantially centrally of said trough and a rotatable screen mounted upon said shaft, an endless conveyor forming the bottom of said trough and operating parallel with said screen throughout its length, a division wall mounted in proximity to the medial line of said trough, and forming a support for one end of said shaft, said hopper forming a support for one end of said shaft, said hopper forming a bearing support for the other end of said shaft.
7. A device of the character described, including a trough, a hopper at one end of said trough, a shaft mounted parallel and substantially centrally of said trough and a rotatable screen mounted upon said shaft, an endless conveyor forming the bottom of said trough and operating parallel with said screen, throughout its length, a division wall mounted in proximity to the medial line of said trough, and forming a support for one end of said shaft, said hopper forming a bearing support for the other end of said shaft, said screen being cylindrical and having its ends open.
8. A device of the character described, including a trough, a hopper at one end of said trough, a shaft mounted parallel and substantially centrally of said trough and a rotatable screen mounted upon said shaft, an endless conveyor forming the bottom of said trough and operating parallel with said screen throughout its length, a division wall mounted in proximity to the medial line of said trough, and forming a support for one end of said shaft, said hopper forming a bearing support for the other end of said shaft, said screen being cylindrical and having its ends open; said hopper having an outlet into one of said open ends.
9. A device of the character described, including a trough, a hopper at one end of said trough, a shaft mounted parallel and substantially centrally of said trough and a rotatable screen mounted upon said shaft, an endless conveyor forming the bottom of said trough and operating parallel with said screen throughout its length, a division wall mounted in proximity to the medial line of said trough, and forming a support for one end of said shaft, said hopper forming a bearing support for the other end of said shaft, said screen being cylindrical and having its ends open, said hopper having an outlet into one of said open ends, a shaft mounted transversely of said trough and gears connecting said shafts.
10. A device of the character described, including a trough, a hopper at one end of said trough, a shaft mounted parallel and substantially centrally of said trough and a rotatable screen mounted upon said shaft, an endless conveyor forming the bottom of said trough and operating parallel with said screen throughout its length, a division wall mounted in proximity to the medial line of said trough, and forming a support for one end of said shaft, said hopper forming a sprocket shaft over which said conveyor operates.
11. A device of the character described, including a trough, a hopper at one end of said trough, a shaft mounted parallel and substantially centrally of said trough and a rotatable screen mounted upon said shaft, an endless conveyor forming the bottom of said trough and operating parallel with said screen throughout its length, a division wall mounted in proximity to the medial line of said trough, and forming a support for one end of said shaft, said hopper forming a bearing support for the other end of said shaft, said screen being cylindrical and having its ends open, said hopper having an outlet into one of said open ends, a shaft mounted transversely of said trough and gears connecting said shafts, a sprocket shaft over which said conveyor operates.
12. A device of the character described, including a trough, a hopper at one end of said trough, a shaft mounted parallel and substantially centrally of said trough and a rotatable screen mounted upon said shaft, an endless conveyor forming the bottom of said trough and operating parallel with said screen throughout its length, a division wall mounted in proximity to the medial line of said trough, and forming a support for one end of said shaft, said hopper forming a bearing support for the other end of said shaft, said screen being cylindrical and having its ends open.

bearing support for the other end of said shaft, said screen being cylindrical and having its ends open, said hopper having an outlet into one of said open ends, a shaft 5 mounted transversely of said trough and gears connecting said shaft, a sprocket shaft over which said conveyor operates, a common means for operating all of said shafts.

11. A device of the character described, 10 including a trough, a hopper at one end of said trough, a shaft mounted parallel and substantially centrally of said trough and a rotatable screen mounted upon said shaft, an endless conveyor forming the bottom of 15 said trough and operating parallel with said screen, a division wall mounted in proximity to the medial line of said trough, and forming a support for one end of said shaft, said hopper forming a bearing support for the 20 other end of said shaft, said screen being cylindrical and having its ends open, said hopper having an outlet into one of said open ends, a shaft mounted transversely of said trough and gears connecting said 25 shafts, a sprocket shaft over which said conveyor operates, a common means for operating all of said shafts; an agitator within said hopper and means connected with said last means for operating said agitator.
- 30 12. A device of the character described, including a trough, a hopper at one end of said trough, a shaft mounted parallel and substantially centrally of said trough and a rotatable screen mounted upon said shaft, 35 an endless conveyor forming the bottom of said trough and operating parallel with said screen, a division wall mounted in proximity to the medial line of said trough, and form-

ing a support for one end of said shaft, said division wall forming two passageways. 40

13. A device of the character described, including a trough, a hopper at one end of said trough, a shaft mounted parallel and substantially centrally of said trough, and a rotatable screen mounted upon said shaft, 45 an endless conveyor forming the bottom of said trough and operating parallel with said screen, a division wall mounted in proximity to the medial line of said trough, and forming a support for one end of said shaft, said 50 division wall forming two passageways, a guide adjacent the free end of said screen for directing potatoes into one of said passageways.

14. A device of the character described, 55 including a trough, a hopper at one end of said trough, a shaft mounted parallel and substantially centrally of said trough, and a rotatable screen mounted upon said shaft, an endless conveyor forming the bottom of 60 said trough and operating parallel with said screen, a division wall mounted in proximity to the medial line of said trough, and forming a support for one end of said shaft, said division wall forming two passageways, a 65 guide adjacent the free end of said screen for directing potatoes into one of said passageways, said screen having a free open end aligning with the other of said passageways. 70

In testimony whereof I affix my signature in the presence of two witnesses.

CARL M. HANNA.
